(57) CLAIM

I claim the ornamental design for a soundbar, as shown and described.

DESCRIPTION

FIG. 1 shows a front perspective view of the soundbar;

FIG. 2 shows a front view of the soundbar;

FIG. 3 shows a rear view of the soundbar;

FIG. 4 shows a first side view of the soundbar;

FIG. 5 shows a second side view of the soundbar;

FIG. 6 shows a top view of the soundbar; and,

FIG. 7 shows a bottom view of the soundbar.

The broken lines shown are included for the purpose of illustrating portions of the soundbar that form no part of the claim.
